Blust & Harbster,

Churk.

NO. 100,969.

Patented Mar. 22, 1870.

United States Patent Office.

C. BLUST, OF LUCAS, OHIO, AND MATTHAU HARBSTER, OF READING, PENNSYLVANIA, ASSIGNORS TO C. BLUST.

Letters Patent No. 100,969, dated March 22, 1870.

IMPROVEMENT IN CHURN-DASHER CRANK-FIXTURES.

The Schedule referred to in these Letters Patent and making part of the same.

To all whom it may concern:

Be it known that we, C. BLUST, of Lucas, in the county of Richland and State of Ohio, and MATTHAU HARBSTER, of Reading, in the county of Berks and State of Pennsylvania, have invented a new and useful Improvement in Churn-Dash Crank-Fixtures; and we do hereby declare that the following is a full, clear, and exact description thereof, which will enable others skilled in the art to make and use the same, reference being had to the accompanying drawings forming part of this specification.

Figure 1 is a detail sectional view of my improved fixtures.

Figure 2 is a detail sectional view of the same, taken through the line x x , fig. 1.

Figures 3, 4, and 5 are detail views of various parts of the fixtures.

Similar letters of reference indicate corresponding parts.

Our invention has for its object to improve the construction of the crank and other fixtures by means of which a horizontal churn-dasher is operated, so as to simplify their construction and at the same time enable the dasher to be easily operated and conveniently removed from the churn-body when required; and

It consists in the construction and combination of the various fixtures as hereinafter more fully described.

A is the bracket, by means of which the crank B is connected with the churn-body, and which is made with three radial arms, a^1 having holes through their ends to receive the screws to secure it to the churn-body.

a^2 are three arms projecting from the arms a^1 , and at the outer end of which is formed the outer bearing a^3 , for the crank-shaft b' .

The inner bearing a^4 for said shafts is formed in the middle of the base-plate of the bracket A.

The inner bearing or socket a^4 projects beyond the base of the bracket A far enough to pass through the side of the churn, and is made slightly tapering, so that it may be driven firmly into the hole formed in the side of the churn-body to receive it.

B is the crank, the shaft b' of which passes through and works in the bearings a^3 a^4 of the brackets A.

Through the middle part of the shaft b' are formed two holes to receive the wedge keys C C', which rest against the bearings a^3 a^4 , and prevent all longitudinal movement of said crank-shaft while being used.

Upon the inner end of the shaft b' is formed a square tapering tenon, which enters a square socket in the plate D, attached to the end of the dasher.

In the outer end of the bearing a^4 is formed a stuffing-box or recess, in which is placed a leather, gum-elastic, or other suitable packing, E, to prevent the contents of the churn from leaking out around the shaft b' .

The packing E may be kept in place by the key c, or by an iron washer, F, interposed between the said packing and key, as shown in figs 1 and 2.

G is a plate, having a pivot projecting from its middle part and cast solid with it.

H is a plate which is designed to be let into a hole bored in the inner surface of the churn-body, and which is cast with a socket formed in it to receive the pivot of the plate G. By this construction, by removing the outer key c', the crank B may be drawn outward until the inner end of its shaft b' is flush with the inner surface of the churn-body, allowing the churn-dash to be conveniently removed.

Having thus described our invention,

What we claim as new, and desire to secure by Letters Patent, is—

1. A removable crank-shaft, b' , perforated at two points, and provided with wedges C C' to hold it in position, and to admit of its entire or partial removal, as shown and described.

2. The combination in the barrel of a churn of the flanged and recessed hub a^4 , rubber packing E, and metal washer F, to form a firm milk-tight bearing for the actuating-shaft, in the manner set forth.

C. BLUST.

Witnesses: MATTHAU HARBSTER.

A. HOWARTH,
GEORGE REID.
